Atty.

UNITED STATES PATENT OFFICE

JOHN C. SHERMAN, OF GORHAM, MAINE

RAZOR

Application filed October 22, 1929. Serial No. 401,402.

This invention relates to improvements in a safety razor and blades therefor. One of the most well-known and widely used razors on the market is made of three separate pieces which when in use are secured together to clamp a blade in place. The task of removing a used blade after a shave is messy and somewhat dangerous owing to the necessity of handling the two-edged blade and the consequent liability of the blade to slip and cut the operator's fingers. According to the present invention, a razor and a blade are provided which are so connected that a blade can be readily picked up by and released from the razor without being touched by the operator's fingers. The usual structure of a razor of the type referred to includes a guard with a hollow shank attached at right angles thereto, a cap adapted to be drawn against the guard so as to clamp a blade between it and the guard, and an elongated cylindrical nut adapted to extend through the hollow shank for threaded engagement with a threaded stud projecting from the plate so that by rotation of the nut, the plate is drawn against the guard. According to the invention the guard and shank may be so modified in structure as to permit a blade to be held firmly but releasably in contact with the face of the guard without the aid of the plate. To this end a pair of gripping elements which may take the form of small hooks or catches, may be mounted in the guard to project from the face thereof. These gripping elements are movable a small distance toward each other so as to enter a pair of apertures in the blade which are so spaced that when the said elements move away from each other to their normal distance apart, they engage on the mutually remote sides of the apertures. The remote sides of the apertures preferably have a V-shape or its equivalent so that the gripping elements are wedged in the converging sides of the V, and hold the blade firmly against side play.

To facilitate mutual approaching movement by the gripping elements, the guard itself may be in two parts separated by a transverse slot which extends a sufficient distance up the shank to permit an operator to

pinch the parts of the guard together against the resilience of the split shank to permit the gripping elements to enter or leave the apertures in the blade which are designed to receive them.

For a more complete disclosure of the invention reference may be had to the description thereof which follows, and to the illustration thereof on the accompanying drawings, of which,

Figure 1 is a perspective view of the guard and shank portions of a razor embodying the invention.

Figure 2 is a blade adapted for use with the shanks shown in Figure 1.

Figure 3 is a perspective view of a cap for use with the parts shown in Figure 1.

Figure 4 is a perspective view of a package of razor blades.

Figure 5 is a section on line 5—5 of Figure 1.

Figure 6 is a section of the guard and a blade showing the parts of the guard sprung toward each other to engage or release the blade.

Figure 7 is similar to Figure 6, but with the cap also shown in section.

Referring to the drawings in detail, Figures 1, 2 and 3 illustrate a razor embodying the invention, this razor having the general construction of a well known type of safety razor, the component parts of which include a guard plate 10 to which is permanently secured a hollow shank 11. The guard plate 10, as shown, may be somewhat curved so that its lower face has a surface in the form of a segment of a cylinder or otherwise shaped as desired. A wafer blade 12 is adapted to be sprung slightly about the curved face of the guard 10 by a cap 13, the blade being clamped tightly between the guard 10 and the cap 13 in a manner well known in the art. To this end a cylindrical nut 14 extends downwardly through the hollow shank 11, the upper end of the nut being provided with a knurled head or finger-piece 15, the lower end being in threaded engagement with a portion of the cap 13. As shown, this threaded engagement may be between a threaded stud 16 permanently secured to the

upper face of the cap 13 and the interiorly threaded lower end portion of the nut 14, as shown in Figure 7. The cap 13 may also be provided with a pair of pins or studs 17 projecting from its upper face and adapted to pass through a corresponding pair of perforations 18 in the guard 10, this being for the purpose of holding the blade 12 properly aligned with the guard when clamped in place. When the parts of the razor are being assembled, the studs 17 serve to guide the cap 13 into correct alignment with the guard. The blade itself is provided with suitable perforations 19, 20, 21 through which the pins 17 and the stud 16 may pass.

The purpose of the present invention is to provide means by which the blade 12 may be gripped and firmly held in place adjacent to the lower face of the guard 10 when the cap 13 is not assembled therewith. To this end a pair of gripping elements or catches 22, which may be hooked as shown are mounted so as to project downwardly from the lower face of the guard 10. As shown in Figure 5, each gripping element may take the form of a knob 22 with a recess 23 adapted to engage the side walls of a suitable perforation 24 through the blade 12 after the head of the knob 22 has been passed through the perforation. For convenience of manufacture, the knob 22 may be riveted to the guard 10, or may be otherwise fastened thereto as by welding or soldering. As shown in Figure 2, a pair of perforations 24 are shown to receive a corresponding pair of catches 22 which are mounted on the guard 10.

As shown in Figure 1, the guard 10 is bisected by a transverse slot 25 which extends upwardly through a portion of the hollow shank 11 and thus splits the shank for a considerable distance. The two portions of the guard are thus separately united to the split end portions of the shank and may thus be moved a short distance toward each other by pinching a split portion of the shank. This approaching motion of the two parts of the guard results in a similar approach of the two catches 22 which are carried respectively by the guard portions. The holes 24 in the blade 12 are suitably spaced so as to receive the catches 22 only when they are made to approach each other as by pinching the guard sections together or by pressing downwardly upon the knurled head of the nut 14, so as to cause downward pressure upon the hollow shank 11 and guard 10, thereby causing the curved surfaces of the catches 22 to press against the edge of the apertures or perforations 24 and thus spring the hollow shank as when squeezed by the user's fingers. The lower end portion of the nut 14 may be tapered as shown in Figure 7 to permit the split shank portions to be sprung toward each other while the nut is in the shank. Due

70 the shank, the guard parts and the catches 22 spring back to normal position when released. This brings the catches into firm engagement with the mutually remote walls of the two holes 24 which form V-notches, these portions of the walls catching against the necks 23 of the respective catches 22 with a wedging engagement. This ensures a firm grip on the blade and prevents any looseness or play thereof when held by the catches 22. Thus the blade is held firmly but releasably adjacent to the lower face of the guard 10. By pinching the split end portion of the shank 11, as shown in Figure 6, the blade may readily be released and will drop clear of the guard. A blade may readily be picked up by the guard without being touched by the fingers of the operator, this being accomplished by pinching the split end portion of the shank and inserting the catches 22 through the holes 21, then permitting the catches to spring back to their normal position and thus to come into firm wedging engagement with the walls of the holes 24. 80 This wedging engagement may be otherwise accomplished by the user in pressing downwardly upon the knurled head of the nut 14. If the blade to be picked up is lying on a flat surface, the surface should be recessed beneath the apertures 24 to permit the catches 22 to project below the blade. The guard and blade held thereby may then be placed on the cap 13, and the nut 14 may be rotated to draw the cap 13 into clamping engagement with the guard 10, the blade 12 being between these two members, as shown in Figure 7. A pair of suitable holes or recesses 26 may be formed in the upper face of the cap 13 to receive the ends of the catches which project below the blade and thus to permit the cap 13 to be drawn up tightly against the blade 12 and the guard 10.

100 To facilitate the insertion of a new blade in the razor, the blades may be supplied in a convenient package, as illustrated in Figure 4, this package comprising a succession of blades having fiber spacing elements 27 alternating therewith. These elements may be pressed or molded into shape with rectangular recesses 28 in each face thereof to receive the blades. The spacers are also preferably perforated as at 29, these perforations being in registry with the perforations 24 of the plates, so that when the catches 22 are inserted through the holes 24, there will be 110 nothing to prevent their projecting below the bottom of the blade.

115 While I have described and illustrated a package of blades particularly adapted for use with my improved razor, I do not claim herein the package or its elements, these constituting the subject matter of my copending application Serial No. 438,804, filed March 25, 1930.

120 The razor may be operated as follows: By 130

pinching the lower portion of the shank 11 or by pressing downwardly upon the knurled head of the nut 14, the catches 22 are moved sufficiently toward each other to permit them to pass through the apertures 24 of a blade 12. Thus a fresh blade may be picked up from the top of a blade package such as shown in Figure 4. The blade is thus held firmly adjacent to the lower face of the guard 10. The guard and blade are then placed on the cap 13 and the handle 15 is rotated to draw the cap 13 into tight clamping engagement with the blade 12 and the guard 10. The razor is now ready for a shaving operation, after which the cap 13 may be released by unscrewing the nut 14. After the cap 13 is removed, the guard and blade may be held over a suitable receptacle for used blades, whereupon by pinching the lower portion of the shank, the blade will fall into the receptacle. Thus the blade may be inserted and discharged without being touched by the fingers of the operator.

I claim:

25 1. A safety razor comprising a guard, a cap, a blade, means for holding said blade releasably adjacent to said guard, and means for drawing said cap toward said guard to clamp the blade therebetween, said blade having a pair of spaced perforations each including a V-notch, said guard having a pair of spaced catches movable toward each other against a resilient force to enter said perforations and to spring back into wedging engagement with said V-notches.

2. A safety razor comprising a guard, a hollow shank permanently secured to said guard and extending from the upper face thereof, an elongated nut adapted to extend through said shank, a cap having a threaded element for threaded engagement with said nut and adapted to be drawn against said guard, said guard and shank having a transverse slot therein bisecting said guard and dividing the shank for a substantial portion of its length, a pair of catches secured to the lower face of said guard, and a blade having a pair of apertures therethrough to receive said catches when the two sections of the guard are moved toward each other, said apertures each including a V-notch to receive one of said catches in wedging engagement when the catch moves outwardly to normal relative position.

55 3. A safety razor comprising a guard, a cap, a blade, means for gripping and holding said blade releasably adjacent to said guard, means for drawing said cap toward said guard to clamp the blade therebetween, and means for positioning the blade when clamped, said gripping means including a pair of elements substantially spaced apart and relatively movable in the plane of the blade to grip edge portions of the blade, said blade having perforations to receive said clamping means

and positioning means, said blade also having edge portions shaped and located for engagement by said gripping elements.

4. A safety razor comprising a blade, means for positioning the blade therein, and means for picking up a blade including a pair of blade-gripping elements substantially spaced apart and relatively movable in the plane of the blade, said blade being perforated to receive said positioning means and being also provided with edge portions shaped and located for engagement by said gripping elements.

5. A safety razor comprising a blade, a guard, a cap, means on said cap for positioning a blade in the razor, and means for picking up a blade including a pair of blade-gripping elements mounted on said guard and relatively movable in the plane of the blade, said blade being perforated to receive said positioning means and being also provided with edge portions shaped and located for engagement by said gripping elements.

6. A safety razor blade having a pair of perforations to receive blade-positioning means of a razor, a perforation to receive a clamping member of the razor, and a pair of perforations forming internal edge portions shaped and located for engagement by gripping elements on the razor.

7. A safety razor blade perforated to receive therethrough blade-positioning means and a clamping member on a razor, said blade also having a pair of perforations each forming internal edge portions converging toward the adjacent end of the blade and so spaced as to be engaged by blade-gripping elements on the razor when the blade-positioning means is received by the blade.

8. A safety razor blade having a pair of perforations, each of which includes a V-notch located and arranged for wedging engagement with a blade-gripping element on a razor, said blade also having a central perforation to receive a clamping member on said razor.

9. A safety razor blade having perforations to receive blade-positioning means of a razor, said blade also having a pair of perforations which include oppositely extending V-notches located and arranged for wedging engagement with a pair of blade-gripping elements on the razor which are relatively movable in the plane of the blade.

In testimony whereof I have affixed my signature.

JOHN C. SHERMAN.
